UNITED STATES PATENT OFFICE.

LEON STOCKES, OF PHILADELPHIA, PENNSYLVANIA.

AUTOMATIC MUSICAL INSTRUMENT.

No. 798,226.

Specification of Letters Patent.

Patented Aug. 29, 1905.

Application filed January 28, 1904. Renewed February 1, 1905. Serial No. 243,662.

To all whom it may concern:

Be it known that I, LEON STOCKES, a citizen of the United States, residing at Philadelphia, in the county of Philadelphia and State of Pennsylvania, have invented certain new and useful Improvements in Automatic Musical Instruments, of which the following is a specification.

My invention relates to improvements in musical instruments, and particularly to automatic playing instruments.

The object of my invention is to make such improvements in the construction and arrangement of the different parts of the instrument that the same will operate effectively, not get out of order, to simplify the construction, and reduce the cost of manufacture.

A further object of my invention is to provide a revolving drum for carrying the perforated music-sheets so that several different tunes may be played by the instruments automatically.

A further object of my invention is to provide means of revolving said drum automatically after a tune has been played or to revolve said drum by hand, so that any tune may be played that is desired, and also to automatically stop the motor used for operating the parts at the end of each tune and to provide a dial on which is indicated the next tune to be played.

A still further object of my invention is to provide effective mechanical means between the music-sheets and the strings of the instruments to pick said strings and also to operate the neck-piece of the instruments so as to change the length of the open space on the strings for the purpose of making different notes.

A still further object of my invention is to couple two instruments together to increase the volume of music; but means is provided to throw one instrument out of action when desired.

In the drawings, Figure 1 represents a front elevation of my improved musical instrument. Fig. 2 is a vertical sectional view as on line 2 2, Fig. 1. Fig. 3 is a longitudinal sectional view as on line 3 3, Fig. 2. Fig. 4 is a vertical sectional view as on line 4 4, Fig. 3. Fig. 5 is a longitudinal sectional view as on line 5 5, Fig. 1, on a larger scale. Fig. 6 is a longitudinal sectional view as on line 6 6, Fig. 1, on a larger scale. Fig. 7 is a longi-

tudinal sectional view as on line 7 7, Fig. 4, 55 on a larger scale. Fig. 8 is a face view, full size, of the neck-piece of one of the instruments. Fig. 9 is a vertical sectional view as on line 9 9, Fig. 8. Fig. 10 is a diagrammatical view in perspective, showing the means 60 for operating the frets on the neck-piece; and Fig. 11 is a view similar to Fig. 10, but showing the means for picking the strings.

Referring to the drawings, A and A' represent mandolins, which are the kind of instruments used in this instance; but any other string instruments may be used instead. The mandolins are held by bolts a and a' to the casing B. On each instrument is a neck-piece A², over which pass the strings A³, A⁴, A⁵, 70 and A⁶, each consisting of three wires. The neck-piece A² is more clearly shown in Figs. 5, 8, and 9. The strings are stretched from the fret A⁷ to the tailpiece A⁸, and when the string is picked one note will be produced. 75 To produce a different note, the length of the string must be shortened, which is done by having a series of frets C under each string, as shown in Fig. 8. These frets when in their normal position do not touch the strings. 80 Each of said frets C consists of a shaft c, as shown in Fig. 10, said shaft having a blade c' and a segmental gear c². The said shaft is pivotally mounted in the neck-piece, and when turned to the position shown in Fig. 10 the 85 blade c will contact with the string and shorten the length of said string, and a clear tone will be produced when the string is picked. A gear c³, carried by a rock-shaft c⁴, engages the gear c² and operates the same. Separate 90 rock-shaft and segmental gear are provided for each fret, as shown in Figs. 2, 5, 8, and 9. Each rock-shaft c⁴ has an arm c⁵ thereon, to which is connected a wire c⁶, the lower end of said wire being connected to a lever D, 95 which is operated by the sheet of music D¹⁰.

There is a row of levers D, as shown in Figs. 4 and 7. They rest upon the sheet of music, which is of metal and of sufficient strength to support the levers. In the music-sheet are perforations, which pass under the levers as the music-sheet is turned and allow the levers to drop into said perforations and pull the wires c⁶ and operate the frets C. Four of the said levers, as shown at D', D², 100 D³, and D⁴, Fig. 7, operate the mechanism for picking the strings, which is shown in Figs. 2, 6, 7, and 11. The said levers D', D², D³,

and D^4 are connected by wires d' , d^2 , d^3 , and d^4 to arms E on the rock-shafts E' , E^2 , E^3 , and E^4 . Each of said rock-shafts is provided at either end with a segmental gear e , which 5 engages the rack-bars F' , F^2 , F^3 , and F^4 . The rack-bars are provided with cam-surfaces f , which contact with similar cam-surfaces on the picker-bars G' , G^2 , G^3 , and G^4 , which are at right angles to the rack-bars. The picker-bars 10 carry the pickers G , which are of flexible material, such as tortoise-shell. These pickers are drawn over the strings when the wires d' , d^2 , d^3 , or d^4 are pulled downwardly, and when said wires are released the pickers 15 are drawn back to their normal position by the springs g and g' on the picker-bar and rack-bar, respectively.

As shown in Fig. 6, the rack-bars are mounted in bearings F' on the cross-pieces F^6 , which 20 support the rock-shafts E' , E^2 , E^3 , and E^4 . The picker-bars G' , G^2 , G^3 , and G^4 are mounted in a square bar G^5 , secured on an ornamental plate G^7 , as shown in Figs. 1 and 2. The ornamental plate G^7 on one of the mandolins 25 is pivotally mounted on a shaft G^8 , which can be turned by means of the worm-wheel G^9 on said shaft, the worm G^{10} on a vertical shaft G^{11} , the bevel-gears G^{12} , and the longitudinal shaft G^{13} , having a knob G^{14} on the front of 30 the casing, whereby the said ornamental plate G^7 may be swung away from the strings, so that the pickers will not act on said strings, thus preventing one of the mandolins from sounding. The said ornamental plate, however, is not moved sufficiently to disengage 35 the rack-bars from the picker-bars. The said rack-bars may be drawn slightly forward without being disengaged from the segmental gears e .

40 The music-sheets which operate the levers D , as above described, are carried by rolls H , mounted in bearings h on a drum I , which is carried by a vertical shaft i , mounted in bearings i' and i'' . The drum I is revolved so as to bring any one of the music-sheets under the levers D , which said levers are operated by the music-sheet passing under them, the perforations in said music-sheet allowing the said levers to drop. The rolls H , carrying said 45 music-sheets, are turned by a gear-wheel h^2 on the shaft carrying said rolls. The said gear-wheel receives motion through the gear-wheel h^3 on the shaft h^4 , having a pulley h^5 thereon, which is driven by a belt h^6 from the motor W . The rolls H are provided with annular ribs H' , as shown in Fig. 10, to support 50 the music-sheet between the perforations, which are cut in rows. The end ribs H^2 on the said rolls are somewhat larger than the inner ribs and are provided with teeth H^3 , which enter the perforations on the edge of the music-sheets and keep the same from slipping. The music-sheets are made of flexible metal, so that they will hang in a loop from the rolls 55

60 H, which permits the music-sheets to be of sufficient length to play a full tune.

The drum I is provided with radial partitions I' , which keep the music-sheets from touching each other. The levers D are pivoted to a cross-piece d , and their free ends are 65 held in a slotted plate D^1 , which carries springs D^2 to act upon each lever separately, which tend to hold them down upon the music-sheet. The drum I is revolved by the ratchet-wheel K on the shaft i , which is engaged by a pawl 70 on the bar k . The said bar k has an eccentric ring k' formed therein, which encircles the cam L on the shaft L' , so that upon every revolution of the shaft L' the drum will be 75 turned a fraction of a revolution, according to the number of teeth in the ratchet-wheel K , which correspond to the number of music-rolls carried by the drum. To lock the drum 80 in a position where the music-sheet will be under the levers D , a lever M is provided, which is pivoted at m . A pin M' , carried by 85 said lever, is adapted to enter holes in the bottom of the drum and keep said drum from turning. The cam L has a cam-surface l on the top face, which will raise the lever M and 90 release the pin M' on the opposite end of said lever from the drum. The shaft L' may be operated by the handle J' through medium of the shaft J^2 and the bevel-gears J^3 and J^4 when it is desired to turn the drum to select a particular tune, or said shaft may be operated automatically. 95

When a tune has been played, a perforation in the music-sheet will allow the lever D^8 to fall, which by means of the pivoted bar N 100 will separate the gear-wheels h^2 and h^3 , which will stop the music-sheet from revolving. The shaft h^4 , carrying the said gear-wheel h^3 , is mounted in bearings h^6 and h^7 , which are carried by arms extending from a shaft h^8 , 105 pivoted in a bearing h^9 , which will allow the said shaft h^4 to oscillate. When the said lever D^8 has acted, the said shaft h^4 will move sufficiently to bring the bevel-gear j in mesh with the bevel-gear J^4 and turn the vertical 110 shaft L' .

When the shaft L' has been turned one revolution, a new sheet of music will be brought under the levers D . The motor is then stopped by means of the cam L^2 on the shaft L' . The 115 arm P of the bell-crank lever P' drops into the low place on the cam L^2 , which causes the opposite arm P^2 to strike the lever P^3 , which engages a toothed wheel w on the motor-shaft and stops said motor. A cam Q shifts the oscillating shaft back into engagement with the gear-wheel h^3 on the music-roll, so that the said music-roll will be ready to operate 120 when the motor is again started. The starting-lever R is carried by a bearing r , which is pivoted to a fixed bracket r' . To start the machine, the lever R is moved to the left, when its lower end R' will strike the lever P^3 and 125

release the wheel w on the motor-shaft and make contact between the electrical connections P^4 and P^5 , which will start the motor.

When it is desired to select a particular tune, the lever R is forced inwardly against the action of the spring R^2 , when the pin R^3 on said lever will strike the free arm of the ratchet-pawl R^4 , which will release the ratchet-wheel R^5 on the shaft J^2 , so that said shaft 10 may be turned by the handle J' , and thereby turn the drum I until the desired piece of music is brought under the levers D . When the lever R is thus forced in, it will also act on the bell-crank lever S , which through the 15 medium of the bell-crank lever S' and the connecting-rods S^2 and S^3 will raise the end of the oscillating shaft h^4 and separate the gears h^2 and h^3 , so that the music-roll will not turn. The said oscillating shaft is not moved sufficiently to bring the bevel-gears j and J^4 into action. A friction-clutch (not shown) may be provided between the shaft J^2 and the ratchet-pawl R^4 , so that the shaft J^2 can be turned freely when driven by the motor with- 20 25 out turning the handle J' and so that said shaft J^2 can only be turned by the handle J' when the ratchet-wheel R^5 is released from the ratchet-pawl R^4 . To allow the oscillating shaft to be thus moved, it is necessary to free 30 the roller q on the bar q' from the cam Q . This is done by having the bar q' pivoted to the bearing h^7 and its lower end engaged by the connecting-rod S^2 , so that when said connecting-rod is moved the roller q will be 35 moved free of the said cam Q . After the lever R has been thus forced in and the drum I turned by the handle J' and the proper music-roll brought into place the said lever R is forced to the left, as above described, when it 40 45 will act upon the arm P^3 , which will release the motor, and also makes contact between the electrical connections and starts the motor. The said lever R is then released and forced out by the spring R^2 , which brings the gears h^2 and h^3 together, so that motion may be communicated to the roll H from the motor.

A dial T (see Fig. 1) is provided to indicate the next tune to be played. Each piece of 50 music has a number corresponding to the number on the dial, the title of which is printed on a program. The indicator-shaft t has a bevel-gear t' , (shown in Fig. 2,) which meshes with a bevel-gear t'' on a vertical shaft t^3 , having a toothed wheel t^4 , which is turned by pins t^5 , projecting from the drum I . There is a pin for each piece of music, and the movements of the drum will be indicated on the dial.

Having thus described my invention, I claim and desire to secure by Letters Patent—

1. The combination in an automatic musical instrument, of a stringed instrument, a neck-piece, frets pivoted in said neck-piece, rock-

shafts, gears between said rock-shafts, and 65 said frets, an arm on said rock-shaft, a lever, a wire connecting said lever and said rock-shaft, and a perforated music-sheet adapted to control and operate said lever, substantially as described.

70

2. The combination in an automatic musical instrument, of a plurality of stringed instruments, rock-shafts extending between the same, pickers, picker-bars, means of communicating motion from said rock-shafts to said pickers, arms on said rock-shafts, wires attached to the same, levers to operate said wires, and a perforated music-sheet to operate said levers, substantially as described.

75

3. The combination in an automatic musical instrument, of a plurality of stringed instruments, movable frets, rock-shafts, means of communicating motion from said rock-shafts to said frets, pickers, picker-bars, rack-bars contacting with said picker-bars, springs, rock-shafts to operate said rack-bars, an arm on each of said rock-shafts, wires attached to said arms, levers to operate said wires, and a perforated music-sheet to control and operate said levers, substantially as described.

80

4. The combination in an automatic musical instrument, a drum, rolls upon said drum, a series of levers, and means of turning said drum so as to bring the said rolls under said levers, substantially as described.

85

5. The combination in an automatic musical instrument, of a drum, shaft carrying the same, means of revolving said shaft, radial partitions in said drum, rolls mounted in bearings upon the top of said drum, a perforated music-sheet carried by each of said rolls, and means of revolving said rolls, substantially as described.

90

6. The combination in an automatic musical instrument, of a drum, rolls carried by said drum, a gear-wheel on each of said rolls, a gear-wheel upon an oscillating shaft, a motor for driving said oscillating shaft, and means of moving said oscillating shaft to separate said gears, substantially as described.

95

7. The combination in an automatic musical instrument, of a casing, two stringed instruments secured in the same, neck-pieces, movable frets, rock-shafts connecting the frets on either stringed instruments, levers controlling said rock-shafts, pickers, picker-bars, rack-bars, rock-shafts, engaging said rack-bars, levers controlling said rock-shafts, a drum, a plurality of music-sheets carried by said drum, means of rotating said music-sheets, and means of rotating said drum, substantially as described.

100

8. The combination in an automatic musical instrument, of a casing, a drum, music-sheets carried by said drum, levers operated by said music-sheets, stringed instruments, means of playing said instrument by said levers, a dial, a shaft carrying an indicator, a vertical shaft

110

115

120

125

operating the latter shaft, a toothed wheel on said vertical shaft, pins projecting from said drum to engage said tooth-wheel and operate the said indicator, substantially as described.

5 9. The combination in an automatic instrument, of a casing, a drum, music-sheets carried by said drum, levers operated by said music-sheets, stringed instruments, frets controlled by said levers, pickers controlled by
10 said levers, an ornamental plate carrying said

pickers and means of withdrawing said ornamental plate from the strings of said instruments so that said pickers will not act on said strings, substantially as described.

In testimony whereof I affix my signature in 15 presence of two witnesses.
